THE COLUMBIA PLANOGRAPH CO., WASHINGTON, D. C.

UNITED STATES PATENT OFFICE.

FRANK CHRIST, OF TURKEY RIVER, IOWA, ASSIGNOR OF ONE-THIRD TO E. W. CHRIST
AND ONE-THIRD TO L. J. CHRIST, BOTH OF TURKEY RIVER, IOWA.

GATE.

1,173,929.

Specification of Letters Patent.

Patented Feb. 29, 1916.

Application filed July 6, 1915. Serial No. 38,253.

To all whom it may concern:

Be it known that I, FRANK CHRIST, a citizen of the United States, residing at Turkey River, in the county of Clayton and State of Iowa, have invented certain new and useful Improvements in Gates; and I do declare the following to be a full, clear, and exact description of the invention, such as will enable others skilled in the art to which it 5 appertains to make and use the same.

This invention relates to new and useful improvements in gates and more particularly to swinging gates, and the primary object of the invention is to provide an improved gate 15 of this character which may be quickly and easily raised and lowered to permit the same to be swung over snow or other obstacles, or to permit the passage of small stock, thereby facilitating the separation of the same from 20 the large stock.

A further object of the invention is to provide a device of this character which will be simple and durable in construction, easily operated to raise and lower the same, and 25 one which will be found very efficient in operation.

With these and numerous other objects in view, my invention consists of certain novel features of construction, combination and 30 arrangement of parts as will be herein referred to and more particularly pointed out in the specification and claim.

In the accompanying drawings: Figure 1 is a side elevation of the gate in lowered position; Fig. 2 is the same kind of view of the gate in raised position; Fig. 3 is a top plan view of the same.

In describing my invention I shall refer to the drawing in which similar reference 40 characters designate corresponding parts throughout the several views, and in which the numeral 1 designates a vertical support having secured thereto and spaced therefrom by securing members 2, a parallel hinge bar 3 having a cap 4 on its upper end. A substantially rectangular gate 5 made of any desired material with horizontally disposed rails 6 is hinged to the said bar 3 by hinges 7 secured at its top and bottom. The hinge 45 bar 3 has secured near its upper end intermediate the hinges 7 a gate supporting hook 8 for a purpose to be hereinafter more fully set forth. On one side of the rear upright of the gate is fixedly secured a bracket 9 having 50 an outwardly extending body portion. Se-

cured within the body portion of the said bracket and between the same and the rear upright portion of the gate are a pair of pulleys 10 mounted therein in vertical alinement with one another.

An adjusting lever 11 is fulcrumed at one end 12 to the rear upright portion of the said gate intermediate the two pulleys mounted thereon. The opposite end of the said lever 11 has formed thereon a hook 13 adapted to engage one of the horizontally extending rails 6 of the gate. Secured at one end intermediate the ends of the said lever is a cable 14 which is positioned over the upper pulley and under the lower pulley, and has 70 its opposite end secured to the gate supporting hook 8 on the hinge bar 3.

At the forward end of the gate are mounted slidable latch members 15 on vertically disposed guides 16, on the forward up- 75 right portion of the gate.

In operation when the different parts of the gate are assembled as shown in Figs. 1 and 2 of the drawings, the cable 14 which is secured to the adjusting lever 11 is brought 80 upwardly and rearwardly over the upper pulley 10 on the rear upright of the gate, and then down under the lower pulley, and up to the gate supporting hook, to which it is secured. This gate supporting hook is 85 rigidly secured to the hinge bar 3, and owing to the fact that the hinges of the gate are adapted to slide on the said hinge bar, when the lever 11 is moved either upwardly or downwardly and its hooked end engaged 90 with one of the rails 6 of the gate, the gate will through the action of the cable secured to the lever, be raised or lowered and held as desired.

It is obvious that by this simple and yet 95 efficient arrangement of parts I have provided a gate of this character which may be very simply and readily raised or lowered to any desired position, along the hinge bar 3 when desired. The foregoing description 100 of the construction of my improved device, and the manner of applying the same to use will be readily understood and it will be seen that I have provided a simple, inexpensive and efficient means for carrying out 105 the objects of the invention.

While I have particularly described the elements best adapted to perform the functions set forth, it is obvious that various changes in form, proportion and in the 110

minor details of construction may be resorted to within the scope of the appended claim without departing from the spirit or sacrificing any of the features of the invention.

I claim as my invention:

The combination with a hinge bar suitably mounted parallel to a vertical support, of a substantially rectangular gate with horizontally extending rails connected by vertical uprights at either end having its rear upright adjustably hinged at the top and bottom to said bar, an adjusting lever fulcrumed at one end intermediate the ends of said rear upright and extending forwardly from the same, a bracket having an outwardly extending body portion with laterally projecting feet secured to the same side of the rear upright to which the adjusting lever is fulcrumed, a pair of pulleys mounted between the body portion of the bracket and said upright in vertical alinement, a

gate supporting hook mounted on the hinge bar and spaced a short distance below the upper hinge, a cable connected at one end to 25 the gate supporting hook and extending downwardly and under the lowermost pulley and then upwardly and over the upper pulley, said cable having its free end extending forwardly and secured to the adjusting lever adjacent the fulcrumed end of the same, and a hook arranged on the forward end of 30 said lever adapted to engage one of the horizontally extending rails on said gate whereby upon movement of the lever to different 35 rails, the gate is vertically adjustable to various positions.

In testimony whereof I have hereunto set my hand in presence of two subscribing witnesses.

FRANK CHRIST.
